(57) **CLAIM**

The ornamental design for a t-shirt, substantially as shown and described.

DESCRIPTION

FIG. 1 is a right side view of the t-shirt design;
 FIG. 2 is a front view of the t-shirt of FIG. 1;
 FIG. 3 is a back view of the t-shirt of FIG. 1;
 FIG. 4 is a left side view of the t-shirt of FIG. 1;
 FIG. 5 is a top view of the t-shirt of FIG. 1;
 FIG. 6 is a top view of the t-shirt of FIG. 1; and,
 FIG. 7 is an enlarged fragmentary view of the underside of
 the front, rights bottom corner of the t-shirt in FIG. 1.
 The dashed lines in the drawings represent stitching and the
 broken lines in FIG. 7 represent the edge of the fragmentary
 view.
